UNITED STATES PATENT OFFICE.

FERNAND EDOUARD BOCQUET, OF PARIS, FRANCE.

SKELETON FOR PIPES, RESERVOIRS, AND THE LIKE OF STRENGTHENED CEMENT AND CONCRETE.

No. 840,293.

Specification of Letters Patent.

Patented Jan. 1, 1907.

Application filed March 29, 1901. Serial No. 58,580.

To all whom it may concern:

Be it known that I, FERNAND EDOUARD BOCQUET, of Boulevard Haussmann, Paris, France, have invented a certain new and useful Skeleton for Pipes, Reservoirs, and the Like of Strengthened Cement and Concrete, of which the following is a full and exact description,

This invention relates to an arrangement of metallic skeleton or frame for the manufacture of reservoir-pipes of a shape more especially cylindrical and of similar constructions in strengthened cement and rendering them suitable to withstand great external as well as internal pressure.

In the accompanying drawings, Figure 1 is an end view of a pipe constructed according to my invention. Fig. 2 is a side elevation with a part of the cement outer covering broken away to show the internal construction. Fig. 3 is an end view of a modification, and Fig. 4 is a side elevation showing a method of joining the pipes end to end.

This skeleton is composed, first, of a frame of metallic grating, trellis, or lattice *a*, afterward covered by one or more layers of metal wire *b*, wound in helical, spiral, or similar fashion and joined together or more or less brought together, this wire thereby forming a kind of hoop upon the frame of metallic trellis-work. The grating or metallic trellis may be of any kind; but I wish to state that the well-known trellis-work known by the name of "expanded metal" or "expanded metal lathing" can be used with advantage.

It is to be noted that in the case of the closed spirals the skeleton forms a pipe which already possesses in itself a considerable resistance and staunchness more or less perfect, according to the number of superposed layers in which the metallic wire is wound.

Such a skeleton can replace with advantage the riveted metal plate hitherto generally used in the construction of pipes or tubes of strengthened cement. It possesses all the

advantages of such a plate from the point of view of tangential and longitudinal resistance as well as staunchness or tightness.

I may also place above the one or more wire layers a second cylinder of metallic trellis-work *a'*, itself hooped at *b'*, if necessary, by a spiral winding of wire joined together or otherwise. The pipe would thus be composed of two concentric pipes made of strengthened cement. Between the interior and the incasing pipe may be inserted a winding of some fabric or cloth *C*, suitably coated with asphalt, bitumen, or similar substance. Sleeves or sockets *s*, of strengthened cement, similarly formed may be used to secure the joint between adjoining sections.

I do not limit myself to any particular method or process of manufacture for the construction of this metallic skeleton, and it is to be understood when I say that it is intended for constructions in strengthened cement that the word "cement" is taken in its most general acceptance and that I understand by that both cement or mortar, concrete, or beton of cement proper, as also other materials, such as asphalt or special mortars, or even metals of a fusibility lower than that of the metallic trellis.

As regards the method of uniting to the skeleton the cement, concrete, or material taking the place thereof, I may use any particular method or process of manufacture.

I claim as my invention—

A compound cement pipe, comprising a number of concentric trellis-work skeletons, convolutions of wire coiled around each of said trellis-work skeletons, and a fabric between each of the convolutions of wire and the next outer trellis-work skeleton.

In testimony whereof I have signed my name to this specification in the presence of two subscribing witnesses.

FERNAND EDOUARD BOCQUET.
